UNITED STATES PATENT OFFICE.

FRANK H. HILL AND HARVEY JEFFREY, OF GRAND FORKS, NORTH DAKOTA, AS-SIGNORS OF ONE-THIRD TO OSCAR KNUDSON, OF GRAND FORKS, NORTH DAKOTA.

RAILWAY-CAR SEAT.

1,238,913.

Specification of Letters Patent. Patented Sept. 4, 1917.

Application filed October 28, 1916. Serial No. 128,312.

To all whom it may concern:

Be it known that we, FRANK H. HILL and HARVEY JEFFREY, citizens of the United States, residing at Grand Forks, in the 5 county of Grand Forks and State of North Dakota, have invented certain new and useful Improvements in Railway-Car Seats, of which the following is a specification, reference being had to the accompanying drawings.

This invention relates to railway car seats and particularly to improvements in that form of car seat now commonly used as a standard seat in ordinary day coaches 15 wherein one end of the seat is mounted on a pedestal, the other end of the seat being operatively supported on the wall of the car.

While seats of this character have been adopted as standard railway equipment they 20 are open to the objection, which is common to other forms of car seats, that it is difficult to sweep and clean beneath the car seats, it is difficult to obtain access to the steam pipes which extend along parallel to 25 the baseboard of the car and clean between these pipes and behind them and further that if the pedestal is damaged in any part it is necessary to remove the car seat and replace the entire pedestal at a considerable 30 cost and with some damage to the car itself inasmuch as the screws holding the pedestal to the floor of the car have to be removed and the new pedestal replaced and new screws inserted.

The general object of our invention is to 35 so improve or modify this form of standard seat that the seats of the car may be turned up (end over end) to thereby permit access to be readily had to the space beneath the 40 seats and to the base board of the car and the pipes extending therewith, thus permitting repairs to be made and dirt removed, which dirt now accumulates behind the heater pipes and causes insanitary conditions.

A further object of the invention is to 45 provide a pivotal mounting for the seat upon the supporting pedestal which will permit the ready detachment of the seat 50 from the pedestal and permit the replace-

ment of that part of the car seat support which is most likely to be broken, the construction further permitting of the ready removal of the seats of a car when the car is "shopped".

55

Other objects of this invention will appear in the course of the following description.

The invention is illustrated in the accompanying drawings, wherein,

Figure 1 is a face view of a car seat constructed in accordance with our invention, the pedestal being partly in section and the locking member being in section;

Figure 2 is a transverse sectional view of the car seat and part of the pedestal;

60

Figure 3 is a face view of the end member 28 of the car seat;

Figure 4 is a face view of the plate 34; and

Figure 5 is a fragmentary elevation of the inner face of the plate 28.

65

Referring to these drawings it will be seen that the seat proper is illustrated as comprising the longitudinally extending beams 10 supporting a seat plate 11 upon which the cushion 12 is mounted. The frame composed of the beams 10 and the plate 11 carries at its outer end the usual arm rest 13.

The outer end of the seat is supported upon the pedestal 14 which is formed of a hollow casting and which tapers upward and which, at its upper end, is transversely slotted as at 15 and formed with the oppositely disposed pintle barrels 16 spaced from each other.

80

Attached to the beams 10 in any suitable manner is a metallic frame designated generally 17 which has formed upon it the transversely extending member 18 having a perforated lug 19 which extends into the space between the pintle barrels and is 90 hingedly connected thereto by a pintle bolt 20 which passes through the pintle barrels and through the lug. The transversely extending member 18 is illustrated as having a transversely concave under face 21 which 95 fits upon and has rotative engagement with the exterior faces of these pintle barrels.

Extending downward from the transverse member 18 is an integral bracket 22 which, when the seat is horizontal, is adapted to fit 100

within the slot 15, this bracket carrying upon it the outwardly projecting central hub or boss 23. Adjacent the opposite end of the seat there is provided a downwardly extending bracket 24 having a boss or hub 25 and pivotally mounted upon these bosses 23 and 25 are the rockers 26 which carry the longitudinally extending foot rests 27. This is the ordinary construction in seats of this character. It will be seen that when one of the foot rests is disposed in an operative position, the under face of the other foot rest bears against the seat supporting frame and that the foot rest may be shifted into or out of operative position in accordance with the shifting of the seat back. We have not illustrated this seat back nor the means for supporting it as it is well known and forms no part of our present invention. The outer end of the seat, that is, that end of the seat which is adjacent the wall of the car, is formed by a plate or casting 28, this casting having sockets 29 for the reception of the beams 10 and on its outer face being formed with the upwardly and convergently extending guide lugs 30 and above these guide lugs with a pivoted latch 31 having a detent 32. Mounted upon the base board 33 of the car is a plate 34, the face of which is provided with an integral upwardly extending tongue 35, the side faces of which are upwardly and inwardly inclined and the upper end of which is provided with the laterally projecting tooth 36. The guide ribs 30 coact with this tongue 35 and guide the seat downward upon the wall plate so that the latch 31 will engage with the tooth 36 and lock the seat in its lowered position, the guide ribs 30 engaging with the side faces of the tongue 35. The plate 34 is also formed with the lugs 37 which project outward and engage with the upwardly inclined faces 38 of the plate 28 so as to form a firm support for the outer end of the seat, that is the end toward the wall. The usual steam pipes 39 extend along parallel to the base board of the car and beneath the seat when the seat is in a horizontal position.

Under normal circumstances the seats of the car are arranged in a horizontal position with the tongues 35 in engagement with the latches 31. Now if it be desired for any reason to obtain access to the steam pipes or to the space between the steam pipes and the base board, it is only necessary to release the latch 31 from its engagement with the tongue 35 and then the seat may be turned upon the pivot bolt 20 to a vertical position. Under these circumstances the steam pipes may be readily cleansed and the dirt removed from between the pipes and from between the pipes and the base board. Access may also be had to all that portion of the floor normally covered by the seat and

any repairs may be readily made after which 65 the seat may be returned to its horizontal position and is automatically locked by the latch 31 engaging with the tooth 36.

It will be seen that the modifications or improvements which we have devised for 70 this standard form of car seat do not in any way interfere with the operation of the seat and change the form of the seat but little. The construction is particularly useful when cars are "shopped" as the seat may 75 be readily removed by removing the bolt 20 and without the necessity of removing the screws which hold the pedestal 14 to the floor. Furthermore this improvement will reduce the cost of repairs inasmuch as if 80 the upper portion of the car seat support is broken it is only necessary to remove the pintle bolt 20, replace the seat supporting casting 17 and replace the seat without the necessity of removing the lower portion of 85 the pedestal, whereas at the present time if the seat leg or pedestal is broken in any part it is necessary to discard all of it. This removal of the pedestal and its replacing also damages the car floors by necessitating 90 the removal of screws and their re-application. It will be obvious that no screws need be removed in order to remove the car seat.

While we have shown a form of our invention which is particularly adapted to standard car seats of the character disclosed, yet 95 it will be obvious that the principle of the invention may be applied to other forms of car seats and that various modifications may be made in the detailed construction without 100 departing from the spirit of the invention.

Having described the invention, what we claim is:

1. In a car structure, a supporting pedestal spaced from the wall of the car and having a vertically extending slot and spaced pintle barrels on each side of the slot, a seat supporting frame having a downwardly extending lug insertible in said slot when the frame is in a horizontal position, said 105 lug at its upper end having a transverse perforation for the passage of a pintle bolt which pivotally connects the seat supporting frame to the barrels, and means on the wall of the car for supporting the free end 110 of the frame when the latter is in a horizontal position.

2. In a car structure, a supporting pedestal vertically slotted and having at its upper end laterally spaced pintle barrels, a seat 120 supporting frame having adjacent one end a downwardly extending lug accommodated in said slot when the frame is in a horizontal position, a pintle passing through the upper end of said lug and through the pintle barrels, means upon the wall of the car for supporting the free end of the frame in a 125 horizontal position, a bracket extending

downward from the free end of the frame and having an inwardly extending boss, a boss extending inward from the lug, and a foot rest comprising a pair of rocker arms pivoted to said bosses and carrying longitudinally extending foot supporting bars.

In testimony whereof we hereunto affix

our signatures in the presence of two witnesses.

FRANK H. HILL.
HARVEY JEFFREY.
